UNITED STATES PATENT OFFICE.

WILLIAM HORACE SODEAU, OF NEWCASTLE-UPON-TYNE, ENGLAND, ASSIGNOR TO SIR W. G. ARMSTRONG WHITWORTH & COMPANY LIMITED, OF NEWCASTLE-UPON-TYNE, ENGLAND.

PERCUSSIVE IGNITION DEVICE.

1,009,024.

Specification of Letters Patent. Patented Nov. 14, 1911.

Original application filed March 25, 1907, Serial No. 364,519. Divided and this application filed November 12, 1909. Serial No. 527,740.

To all whom it may concern:

Be it known that I, WILLIAM HORACE SODEAU, a subject of the King of Great Britain and Ireland, and residing at Elswick Works, Newcastle-upon-Tyne, in the county of Northumberland, England, have invented certain new and useful Improvements in Percussive Ignition Devices, of which the following is a specification.

10 This invention relates to percussion igniter devices operated by fluid pressure especially such as are applicable to compressed air heating apparatus.

Percussion igniter devices are already known in which compressed fluid releases a locking mechanism, spring or the like, effecting thereafter a collision between the striker and the primer. Such devices however, are usually complicated in design and 20 possess the great disadvantage that owing to vibrations or the like the locking mechanism may be unintentionally released and result in a premature ignition.

The object of the present invention is to 25 overcome these disadvantages and to produce an igniter which shall be simple in construction and reliable in action.

The invention consists for this purpose in a percussion igniter in which the striking 30 of the moving member against the fixed member is effected by fluid pressure, thus dispensing with springs and the necessary trip devices to hold said springs in this stressed position. By this means premature 35 operation of the igniter by accidental release of the trip device is avoided.

Referring now to the accompanying drawings:—Figure 1 shows diagrammatically one form of the ignition device as applied to air heating plant suitable for torpedoes. Fig. 40 2 shows in section a modified form of the ignition device in which the striker is out of contact with the primer. Fig. 3 shows in detail and on a larger scale the lower 45 recess provided in the piston and on the inner side of the cylinder wall as well as the spring engaging therein. Fig. 4 shows the ignition device according to Fig. 2 after the ignition has been effected. Fig. 5 is a section and Fig. 6 a plan view of the split ring 50 which is used in connection with the modified form of the igniter device.

One form of the invention is shown in Fig. 1 as applied to an air heating plant for

torpedoes, this plant having been already 55 described in detail in my specification, Serial No. 364,519 filed March 25th, 1907. The fluid, hereafter known as air, is stored under pressure in a chamber, *a*, the outlet, *c*, of which is controlled by the valve, *b*, placed 60 in a pipe, *c*, connecting the chamber, *a*, to a reducing valve, *d*, from which the air passes by a pipe, *e*, to the combustion chamber, *f*. Air also passes to the fuel storage chamber, *m*, from the valve, *d*, by a pipe, *i*, 65 and the compressed air to actuate the ignition device, *g*, is supplied from the chamber, *a*, by means of the branch pipe, *k*, leading from the pipe, *c*, in front of the reducing valve, *d*. The fuel is stored in a chamber, 70 *m*, and is conducted by means of the pipe, *n*, terminating in a nozzle, *o*, into the combustion chamber, *f*. By providing a suitable cock, *w*, in the pipe *e*, the pressure of the air in the combustion chamber, *f*, is reduced 75 below that of the air in the fuel chamber, *m*, thereby the fuel is sprayed into the chamber, *f*, and thoroughly mixed with the air ready to be ignited by the ignition device *g*. A cock *j* is preferably provided in order to 80 shut off the air and fuel supply in case of emergency. The cock *w*, can be replaced by any other suitable means which will give the required reduction of pressure. In the ignition device, *g*, the percussion primer *p*, 85 is placed in a suitable case, *q*, to which there is secured a cylindrical liner, *r*, the striker, *s*, which is of a well known form, being carried by the piston, *t*, at the end opposite to the primer, *p*. Previous to the moment of 90 ignition the piston, *t*, is held at the farther end of the liner *r*, by means of a spring, *z*, or the like, but as this spring has practically no duty to perform except when the igniter is in operation it may be made much lighter 95 than the springs in igniters of the type in which the full striking load is always acting on the spring. Instead however, of causing the striker to move against a stationary primer the striker pin may be made stationary and the primer arranged to move. Such a modification of this ignition device has been shown in Figs. 2 and 4, Fig. 2 showing the position of the parts of the ignition device before the compressed air has been admitted to the combustion chamber, *f*. When the air is admitted to the combustion chamber, *f* it exerts pressure on the end of the 100 105

piston, *t*, projecting from the cylinder, *q*, and at the same time passes from said chamber, *f*, between the outer cylinder or casing, *q*, and the sliding piston, *t*, which carries the primer, *p*, and then through the groove, *y*, provided in the outer cylinder *q*, and so presses on the under side of the collar shaped portion of the same. The piston, *t*, is normally held in position by the shearing ring, *z*, shown separately in Figs. 5 and 6, and placed within grooves or recesses, *x* and 2, in the outer cylinder wall and piston respectively. The fluid pressure on the piston, *t*, therefore causes the ring, *z*, to leave the recess, *x*, in the cylinder, this being made possible by forming the recess, *x*, so that its breadth decreases with its depth as shown in Fig. 3, and so forces the piston, *t*, toward the striker, *s*, until the primer, *p*, comes into sudden contact with said striker, *s*, which is carried by the cap, *v*, attached to the cylinder or case, *q*. The combustible in the chamber, *f*, thus becomes ignited while the shearing ring, *z*, is carried within the piston recess, 2, until it springs into another recess, *x'*, in the cylinder wall so placed as to hold the piston, *t*, in its uppermost position with the striker, *s*, in contact with the primer, *p*, as shown in Fig. 4.

30 Many modifications may be made in the details of this ignition device as hereinbefore described. Thus, the primer may be of different form and the spring *z* superseded by a cylindrical spiral spring or other suitable device.

Having now described my invention what I claim as new and desire to secure by Letters Patent is:—

1. A percussion ignition device comprising a cylinder, a piston moving therein, a primer and a striker one of which is carried by said piston while the other is fixed to the cylinder and closes one end thereof and means admitting actuating fluid through the other end of the cylinder to act upon the piston whose consequent movement causes the striker and primer to come into contact.

2. A percussion ignition device comprising a cylinder, a piston moving therein, a primer and a striker one of which is carried by said piston while the other is fixed to the cylinder and closes one end thereof, means admitting actuating fluid through the other end of the cylinder to act upon the piston whose consequent movement causes the striker and primer to come into contact, and means to prevent the operation of the device at times other than when the actuating fluid acts upon the piston.

60 3. A percussion ignition device comprising a cylinder, a piston moving therein, a primer and a striker one of which is carried by said piston while the other is fixed to the cylinder and closes one end thereof, means admitting actuating fluid through the other

end of the cylinder to act upon the piston whose consequent movement causes the striker and primer to come into contact, and means for holding said piston in a fixed position before and after operation of the device. 70

4. A percussion ignition device comprising a cylinder, a piston moving therein, a primer and a striker one of which is carried by said piston while the other is fixed to the cylinder and closes one end thereof, means admitting actuating fluid through the other end of the cylinder to act upon the piston whose consequent movement causes the striker and primer to come into contact, and means for holding said piston in a fixed position before and after operation of the device, said means also acting to prevent operation of the device at times other than when the piston is subjected to the actuating fluid. 80

5. A percussion ignition device comprising in combination a cylinder, a striker rigidly fixed within said cylinder, a primer movable within said cylinder and means for allowing fluid pressure to cause the movement of said primer thereby bringing the primer into contact with the striker. 90

6. A percussion ignition device comprising in combination a cylinder, a striker rigidly fixed within said cylinder, a primer movable within said cylinder, means for allowing fluid pressure to cause the movement of said primer, thereby bringing the primer into contact with the striker, and means for preventing the operation of the ignition device at times other than when the fluid pressure acts upon said primer. 100

7. A percussion ignition device comprising in combination a cylinder, a striker rigidly fixed within said cylinder, a primer movable within said cylinder, means for allowing fluid pressure to cause the movement of said primer thereby bringing the primer into contact with the striker, and means for holding the primer in fixed positions before and after operation of the ignition device. 105

8. A percussion ignition device comprising in combination a cylinder, a striker rigidly fixed within said cylinder, a piston movable within said cylinder, a primer mounted on said piston, and means for allowing fluid pressure to act on said piston whereby the primer is forced into contact with the striker. 115

9. A percussion ignition device comprising in combination a cylinder, a striker rigidly fixed within said cylinder, a piston movable within said cylinder, a primer mounted on said piston, means for allowing fluid under pressure to act on said piston whereby the primer is forced into contact with the striker and means for preventing the operation of the ignition at times other 120

125

130

than when the fluid pressure acts upon said primer.

10. A percussion ignition device comprising in combination a cylinder, a striker rigidly fixed within said cylinder, a piston movable within said cylinder, a primer mounted on said piston, means for allowing fluid under pressure to act on said piston, whereby the primer is forced into contact with the striker, and means for holding said piston in fixed positions before and after operation of the ignition device.

11. A percussion ignition device comprising in combination a cylinder, a striker rigidly fixed within said cylinder, a piston movable within said cylinder, a primer mounted on said piston, means for allowing fluid un-

der pressure to act on said piston whereby the primer is forced into contact with the striker, said piston and cylinder having 20 grooves thereon and a spring placed within said grooves so as to engage the piston and cylinder and thereby to hold the piston in a fixed position before operation of the device and to hold the piston in a position with the 25 primer and striker in contact after operation of the ignition device.

In testimony whereof, I affix my signature in presence of two witnesses.

WILLIAM HORACE SODEAU.
